VEGETABLE AND FRUIT DISPLAY CONTAINER

Filed Nov. 27, 1939

INVENTOR:
VERNON A. PETERSON.
BY MARTIN P. SMITH.

UNITED STATES PATENT OFFICE

2,301,577

VEGETABLE AND FRUIT DISPLAY
CONTAINER

Vernon A. Peterson, Palm Springs, Calif.

Application November 27, 1939, Serial No. 306,241

4 Claims. (Cl. 206—44)

My invention relates to a display rack or container particularly designed for attractively displaying vegetables, fruit, and the like, on the display stands of markets.

The principal objects of my invention are, to generally improve upon and simplify the construction of the existing forms of vegetable display containers and further, to construct the containers with reticulated bottoms, thereby providing for thorough ventilation of the containers and their contents so as to counteract tendency of shrinkage and spoilage of the displayed products, also permitting water that is sprayed onto the vegetables to readily discharge from the containers.

Further objects of my invention are, to provide display containers of the character referred to having simple and efficient means, including handles, that enable the containers to be readily handled while being placed in position upon or removed from the display stands, further, to provide each container with a clip adapted to receive a price tag or the like and further, to provide the containers with readily adjustable partitions or dividers which enables two or more different varieties of vegetables or fruit to be displayed in a single container.

With the foregoing and other objects in view, my invention consists in certain novel features of construction and arrangement of parts that will be hereinafter more fully described and claimed and illustrated in the accompanying drawing in which:

Fig. 1 is a perspective view of a display container constructed in accordance with my invention.

Fig. 2 is a vertical section taken on the line 2—2 of Fig. 1.

Fig. 3 is a cross section taken on the line 3—3 of Fig. 1.

Fig. 4 is an enlarged vertical section taken on the line 4—4 of Fig. 1.

Fig. 5 is a cross section of one of the partitions or dividers that is removably positioned within the container.

Fig. 6 is a sectional view of the upper portion of a display stand of the conventional type used in markets and showing my improved display containers positioned thereon.

Fig. 7 is a side elevational view of a modified form of the display rack or container.

Fig. 8 is a detail sectional view showing a modified form of mounting for the price tag on the rear end wall of the display rack.

Referring by numerals to the accompanying

drawing which illustrates a preferred embodiment of my invention, 10—10 designate the side walls of the container, the same being preferably formed from sheet metal and the height of said walls gradually decreases toward their forward ends. The lower rear corners of the side walls are cut away on inclined lines as designated by 11 and disposed between the forward ends of said side walls is a front wall 12, preferably of sheet metal.

Extending rearwardly from the upper edge of the front wall 12 is a narrow flange 13 and a similar flange 14 extends rearwardly from the lower edge of said front wall.

15 The parallel side members 15 of a frame composed of a narrow strip of metal are positioned against the outer faces of the side walls 10 along the upper edges thereof and narrow portions 16 of said side walls are bent outwardly and downwardly over the members 15 and the parts are suitably secured to each other, for instance, by spot welding or by means of rivets.

20 The frame includes a transverse strip of metal 17 that connects the rear ends of the parallel members 15 between the upper rear corners of the side walls 10 and thus, a substantially U-shaped reinforcing member is provided for the sides and upper rear portion of the container and the front wall 12 and the flanges 13 and 14 25 provide ample reinforcement for the front portion of the container.

30 Upper rear member 17 of the U-shaped reinforcing frame is covered by an inverted U-shaped member 18, preferably formed of sheet metal, and secured to the central portion of this covering member 18 and projecting upwardly therefrom is an inverted U-shaped member 19 that functions as a handle for the rear portion of the container.

35 Suitably secured, preferably by spot welding, 40 to the rear side of the upper cross member of the handle 19 is the rear leg of a U-shaped member 20 formed of resilient metal, the front leg 21 of which extends upwardly in front of the upper cross member of the handle 19, thus 45 providing a clip that exerts pressure against the lower edge of a price card C that is inserted between said clip and the upper portion of the handle (see Fig. 4).

In Fig. 8 I have illustrated a modified form 50 of the price tag holder and this construction comprises a tag holding clip 20a having a lower horizontally disposed U-shaped portion 20b that is adapted to engage with clamping pressure on an inturned flange 18a that projects forwardly from the transverse metal strip 17 that

forms the rear member of the U-shaped reinforcing frame.

An inclined rear wall 22, preferably of sheet metal, connects the inclined rear edges 11 of the side walls 10 and the upper edge of this inclined rear wall is suitably connected to the member 18 that encloses the rear member 17 of the U-shaped frame.

In some instances, it may be found desirable to utilize reticulated material or wire netting 10 in the place of the inclined rear wall 22.

Projecting inwardly from the lower edges of the side walls 10 are flanges 23 and secured to and resting upon said flanges and the flange 14 are the side and front edges respectively of a section 24 of reticulated material, which may be wire mesh, perforated sheet metal, or expanded sheet metal, of the type frequently used in building construction and which may be readily obtained in the open market.

All of the parts of the container are preferably formed from metal and said parts are integrally connected either by spot welding or fastening devices such as rivets and thus, the container and its handle is a practically one piece structure that is capable of withstanding rough usage and the wear and tear to which it may be subjected.

The inwardly turned flange 13 on the upper edge of the front wall 12 provides a convenient ledge to be engaged by the thumb or fingers of the hand while lifting and carrying the container and at the same time, said inwardly turned flange provides a substantial reinforcement for the front end of the container.

In certain vegetable and fruit markets or where the containers are supported on a flat surface or in a stair step arrangement, the containers may be constructed with side walls that are the same height throughout their length with the exception of the inclined rear lower edges 11 and in Fig. 7 I have shown a container of this particular form.

In Fig. 5 I have shown a readily movable partition adapted to be positioned within the container and to extend from front to rear thereof so as to divide the space in the container into separate chambers for the display of fruits and vegetables. This partition or divider is preferably formed of sheet metal and comprises a vertically disposed portion 25 and a horizontally disposed base 26 that is adapted to rest directly on the reticulated member 24.

When used for displaying vegetables, fruit, and the like, the containers may be positioned on a supporting structure or stand as illustrated in Fig. 6 and said containers may be arranged in transverse rows with a plurality of containers in each row, thus attractively displaying a number of different vegetables or fruits in an attractive manner within a limited area.

The use of the containers saves much time and labor in the handling of goods displayed for sale inasmuch as the containers may be filled as the produce is trimmed in the trimming room, after which the filled containers are positioned upon the display stands. Further, the double handling of perishable merchandise is avoided

by merely lifting out one or more of the containers instead of moving the merchandise when the stands are being rearranged or cleaned.

The use of the display containers provides for a uniform price arrangement due to the provision of means for applying a price card to each individual container and in addition to effecting a saving of time and labor in the handling of goods that are removed from stands to be placed in storage boxes and which practice is generally carried out in stores that are closed on Sundays and holidays, the damage and loss of merchandise during such procedure is minimized.

Thus it will be seen that I have provided a vegetable and fruit display container that is relatively simple in construction, inexpensive of manufacture and very effective in performing the functions for which it is intended.

It will be understood that minor changes in 20 the size, form and construction of the various parts of my improved vegetable and fruit display container, may be made and substituted for those herein shown and described, without departing from the spirit of my invention, the scope of 25 which is set forth in the appended claims.

I claim as my invention:

1. A display container comprising a pair of side walls which gradually decrease in height toward their forward ends, a front wall, an inclined rear wall, a reinforcing frame having parallel side members that are secured on the upper edges of the side walls of the container and a rear member that is secured on the upper edge of the inclined rear wall, flanges projecting inwardly from the lower portions of the sides, front and rear walls of the container and a reticulated bottom removably positioned within the container and supported by said flanges.

40 2. A display container as set forth in claim 1 and a handle secured to and projecting upwardly from the central portion of said rear wall.

3. A display container as set forth in claim 1, with a handle secured to and projecting upwardly from the central portion of said rear wall 45 and means on said handle for receiving and holding a price tag.

4. A display container comprising a pair of side walls which gradually decrease in height toward their forward ends, a front wall connecting the forward ends of said side walls, integral flanges projecting rearwardly from the upper and lower edges of said front wall, an inclined rear wall connecting the rear ends of said side walls, flanges projecting inwardly from the lower edges of the side and rear walls, a perforated bottom removably positioned within the container and resting upon the flanges of said side and rear wall and upon the flange projecting inwardly from the lower edge of the front wall, a reinforcing frame having side members that are secured to the upper portions of the side walls of the container and a rear member that is secured to the upper edge of the inclined rear wall of said container and a handle secured to and projecting upwardly from the intermediate portion of said rear wall.

VERNON A. PETERSON.
